METAL FURNITURE CONSTRUCTION

Warren McArthur, Jr., Los Angeles, Calif., assignor, by mesne assignments, to Warren McArthur Corporation, Rome, N. Y., a corporation of New York

Application April 8, 1932, Serial No. 604,043

6 Claims. (Cl. 155—196)

This invention relates to furniture construction and particularly to the construction of metal furniture.

The primary object of the invention is to provide a form of construction for metal furniture that is attractive in appearance, light yet strong, and that can be manufactured, assembled or disassembled cheaply.

A more particular object is to provide a simple and effective method of joining together tubular metal frame members forming elements of furniture.

Still another object is to provide a simple, yet rugged tubular element of furniture, such as the leg of a chair or table.

Other objects and advantages of the invention will be apparent from the following detailed description taken in connection with the drawings, in which:

20 Figure 1 is a perspective view of a chair constructed in accordance with my invention;

Figure 2 is a sectional detail view of fragments of a leg of the chair shown in Figure 1;

25 Figure 3 is a cross-sectional view showing the method of attachment of the back rests of the chair;

Figure 4 is an elevational sectional view showing the method of attachment of the back rests;

Figure 5 is a sectional view illustrating the 30 method of joining four radially extending members to a tubular member;

Figure 6 comprises vertical and horizontal sectional views of one element of my joint construction;

35 Figure 7 is an elevational view of a chair constructed in accordance with my invention;

Figure 8 is a sectional view in the plane VIII—VIII of Figure 7;

Figure 9 illustrates a joint construction alternative to that disclosed in Figures 2 and 6;

Figure 10 is a sectional view in the plane X—X of Figure 9;

Figure 11 is a perspective view of a table having trays attached thereto in accordance with the invention;

Figure 12 is a sectional view through a leg of the table shown in Figure 11;

Figure 13 is a view showing how two lateral members are joined to an upright member in accordance with the practice illustrated in Figures 9 and 10;

Figure 14 is a vertical sectional view in the plane XIV—XIV of Figure 13;

Figure 15 illustrates one of the washers used 55 in the joint shown in Figures 13 and 14;

Figure 16 is a sectional view showing an alternative form of construction to that of Figures 9 and 10, where the lateral member is of large diameter; and

Figure 17 is a detail view partly in section of 5 one form of rung construction.

Referring to Figure 1, I have shown a chair comprising front legs 1, and rear legs 2, the latter extending higher than the front legs 1 to constitute the framework of a back rest. The front 10 legs are joined together by front rungs 3 and 4, and to the back legs by side rungs 5, 6, 7, and 8, and the rear legs are secured together by rear rungs 9 and 10. Slats 11 forming the back rest are secured between the upwardly extending ends of 15 the rear legs 2. An upholstered seat 12 rests upon the front upper rung 4 and the rear upper rung 10. It is prevented from sliding fore and aft by downwardly projecting screws or legs (not shown) which engage with the inner sides of rungs 4 and 20 10 respectively and is prevented from sliding sideways by the upper side rungs 5 and 8.

Each of the legs 1 or 2 is formed of a plurality of tubular members 13 (referring now to Figure 2) separated by washer elements 14 and 15 with 25 which the ends of the rungs engage.

Each washer 14 or 15 may be of circular outline and has formed in its outward face a circular groove 16 into which the adjacent ends of tubular member 13 fit. Each washer also has formed 30 therein a laterally extending opening of roughly semi-cylindrical shape so that when the two co-operating washers 14 and 15 are placed together as shown in Figure 2, they form a laterally extending cylindrical opening flared outwardly at 35 its base as shown at 17 and having a tapered seat 18 at the inner end.

The diameter of the mouth of the lateral opening just described is substantially that of the rung to be inserted therein. Thus, the rung may 40 comprise a piece of metal tubing 19 having its end flared as shown at 20 to fit against the flared wall 17 and thereby anchor the rung between the washers 14 and 15. The end of the rung is preferably reinforced with a plug 21 to increase the 45 strength of the joint.

The joint described is assembled by placing the washers 14 and 15 about the end of the tube 19 constituting the rung, then positioning the tubular members 13 in the seats 16 in the outer faces 50 of the washers and finally compressing the members 13 and the washers 14 and 15 firmly together by tensioning a rod 22 extending therethrough. The rod 22 may be tensioned with respect to the tubular members 13 by mounting washers 23 and 55

24 on the outer ends of the tubular member 13 and screwing nuts 25 and 26 onto the threaded ends of rod 22 against the outer faces of washers 23 and 24.

5 The nut 25 is formed with an ornamental head so that when it has been screwed down to seat against washer 23, it has a neat and finished appearance. The nut 26 on the other hand is designed to be concealed after it is tightened, by 10 an ornamental cap 27 which is threaded onto a threaded shoulder 28 on the nut 26 itself.

The ends of tubes 19 forming the rungs are preferably flared to a slightly larger diameter than the flared seat 17 in the washers 14 and 15 15 so that when the washers are drawn together they clamp firmly about the end of the rung and draw it in against the tapered seat 18, thus forming an absolutely rigid connection and preventing loose joints and resultant squeaking.

20 The washers 14 and 15 may be constructed for the attachment of only one radially extending member 19 as shown in Figure 2 in which case the washers 14 and 15 may be substantially circular in cross section. However, if desired, they 25 may be shaped as shown in Figure 6 in which a projection 29 is formed on the side of the washer to which the rung is attached, the projecting shoulder 29 extending out over the end of the tube 19 a greater distance and thereby forming 30 a more rigid joint.

This form of construction is not limited to the joining of one lateral member only to the vertical member. Thus, as shown in Figure 5, it may be used to secure as many as four radially extending 35 tubular members 19 to a single central post. The construction of the washers shown in Figure 5 is identical with that of washers 14 and 15 described in connection with Figure 2 except that they are provided with four radially extending 40 openings instead of only one.

An alternative form of joint construction to that described in connection with Figures 2, 5, and 6, is disclosed in Figures 9, 10, and 13 to 15. Thus, referring to Figure 9, the tubular member 45 19' forming the rung is not flared at the end but is made straight and is provided with a hole 30 drilled therethrough to receive the rod 22. In this case the washers 14 and 15 are provided with a straight lateral aperture to receive tubular 50 member 19', instead of being flared as shown in Figure 2. With the construction shown in Figures 9 and 10 the tubular member 19' is rigidly secured with respect to the washers 14' and 15' by the rod 22. As described in connection with 55 Figure 2, the end of tube 19' is preferably plugged with a solid plug 21' to strengthen the joint.

In Figures 13 and 14, I have shown a joint construction similar to that of Figures 9 and 10 except that two tubular members 19a and 19b are 60 secured between the same pair of washers 14a and 15a so that two rungs may be joined to the leg of a chair at the same point, as is shown in Figure 1 where the side rungs 6 and 7 intersect the rear rung 9. This form of construction differs 65 from that shown in Figures 9 and 10 in that the washers 14a and 15a are each provided with two semi-cylindrical intersecting grooves 31 and that the ends of the intersecting rungs comprising tubes 19a and 19b are cut away to overlap, thus, 70 as shown in Figure 14, the lower half of the end of tube 19b is cut away and the upper half of tube 19a is cut away so that both tubes when overlapped fit snugly between the washers 14a and 15a. The end of each tube is preferably reinforced by a plug 19c drawn or threaded into the 75

tube. As in the case of the single joint described above, the rungs are retained between the washers 14a and 15a by the rod 22.

In case it is desired to use rungs of large diameter, for instance, diameter comparable to or 5 larger than that of the upright members to which the rungs are attached, the construction disclosed in Figure 16 may be utilized. In this case each rung may be formed of an outer tubular member 32 secured between end members 33; the 10 latter are provided with circular grooves 16' as described in connection with Figure 2, to receive the ends of tube 32 and are retained in position by a central rod 34 which has threaded ends which 15 screw into threaded holes 35 in the end members 33. Each end member 33 is provided with a cylindrical extension 36 having a lateral hole 37 therethrough. A rung as described, when assembled 20 is secured to an upright member in exactly the same manner described in connection with Figures 9 and 10, the small rod-like extension 36 on each end member 33 corresponding to the tubular member 19' in Figures 9 and 10. The inner surfaces 38 on the end members 33 are cylindrical in 25 shape and fit snugly against the outer cylindrical surface of the washers 14' and 15' in Figure 10.

As shown in Figure 1, the front rungs 3 and 4 may be joined by a vertical reinforcing strut 47 of smaller tubing than the rungs. It is preferred 30 to form the rungs 3 and 4 together with the strut 47 as an integral unit before the rungs are 35 assembled in the chair. The construction of the integral unit is clearly shown in Figure 17. Thus, each rung 3 or 4 comprises two pieces of tubing 48 and 49, respectively, positioned end to end with a pair of washers 50 and 51 separating their juxtaposed ends. To center the washers 50 and 51 with respect to each other and to maintain the tubes 48 and 49 in compression against the washers 50 and 51, a central rod 52 is positioned 40 concentrically within the tubes 48 and 49 and maintained in tension between the outer ends of the tubes by means of plugs 53 and 54. These 45 plugs are dimensioned to fit snugly within the tubes 48 and 49 and are provided with hexagonal heads forming shoulders which lie against the ends of tubes 48 and 49. Each plug 53 and 54 contains a threaded central aperture which is 50 adapted to screw onto threaded ends of rod 52. By screwing the plugs 53 and 54 onto the threaded 55 ends of rods 52, the tubes are placed in compression against the washers 50 and 51, and at the same time the rod is placed in tension. Washers 50 and 51 are provided with a longitudinal central opening for centering the rod 52 with 55 respect to the tubes 48 and 49. These washers are also provided with a lateral opening to receive the ends of the strut 47, the latter being provided with a laterally extending aperture at each end through which the rod 52 passes, thus 60 retaining the ends of the strut 47 in proper position between the washers 50 and 51.

The rung structure disclosed in Figure 17 is assembled by threading the tubes 49, washers 51, strut 47, washers 50 and tubes 48 onto rods 52 65 and screwing the plugs 53 tightly onto the opposite ends of rod 52. This clamps the whole assembly firmly together. Thereafter, lateral holes are drilled through the outer ends of tubes 48 and 49 and through the plugs 53 and 54 to provide 70 openings for the central rod 22 of the legs 1. It is obvious that when the chair is assembled and the rods 22 are passed through the registered openings drilled through the ends of tubes 48, 49 and the plugs 53, 54 it will be impossible there- 75

after for the plugs to turn within the tubes and thus decrease the tension of rods 52.

Although any desired metal may be used in constructing chairs or other furniture, as described, I find the methods particularly applicable where the outer tubing members 13 in Figure 2, or 32 in Figure 16, are constructed of aluminum, because the latter metal, although very desirable because of its light weight and attractive appearance, is relatively weak in tension. It is much stronger in compression, however, and may be used successfully for the outer tubular members 13 and 32 for the reason that these members are exposed to compression only. Any tension resulting from the bending of the entire assembly comprising the outer tube and the inner rod 22 or 34 as the case may be, is borne by the inner rod. It is obvious that the outer tubes 13 and 32 cannot be exposed to tensile stress since they are only retained in position by being compressed between the end washers.

I have also found it particularly advantageous to provide the grooves 16 and 16' in the washers used at the ends of the tubular members to conceal these ends. The advantages of this groove are two-fold. In the first place, it conceals the ends of the tubular members so that it is unnecessary to smoothly finish these ends before assembly. This materially reduces the cost of manufacturing the furniture because the lengths of tubing 13 are commonly cut by power saws which leave a ragged burr on the edges of the cut. I find that this ragged burr is really advantageous, as the extra metal completely fills the groove and wedges the tube and washer firmly therein. The second advantage of the groove construction is that it positively centers the ends of the tubular members 13 with respect to the plugs.

Another important advantage of the general method of assembly described, when used in the manufacture of aluminum furniture, is that methods of coloring aluminum have recently been discovered. The colors produced by these methods, however, are not proof against excessive heat and if it is attempted to manufacture aluminum furniture by welding together colored aluminum elements, the color is destroyed by the heat of the weld and the appearance of the completed article is ruined. Furthermore, even the heat incident to sawing the metal may be sufficient to destroy the color immediately adjacent the saw cut. However, the grooves 16' can be made deep enough to conceal the discolored edge so that in accordance with the present process, colored aluminum may be used to advantage to produce beautiful and artistic furniture.

Referring now to the back rest members 11, these are preferably formed of sheet metal slats having their upper and lower edges folded back or rolled to form an edge having a smooth and finished appearance. The ends of these slats are secured within the tubular members 13 as shown in Figures 3 and 4; thus, each slat has a pair of longitudinally extending cuts 39 and 40, respectively, which are positioned equi-distant from the upper and lower edges of the slat and a short distance from the end thereof. In the finished chair the slats are secured within the tubular members 13 by forcing the material above cut 39 and below cut 40 to one side, forcing the material between the cuts 39 and 40 to the opposite side, and passing the tensioning rod 22 through the slots 39 and 40 back of the material be-

tween the cuts 39 and 40 and in front of the material below cut 40. The slit in each tubular member 13 extends to the top of that member, as shown in Figure 4, to permit each slat 11 to be slid along rod 22 into proper position. Of course, the lower slat is first placed in position, then the middle slot, and finally the upper slat, as the tubular sections 13 are built up from the bottom.

It is desirable, in order to prevent undue lateral strain from being transferred from the slats 11 to the rods 22, that the slats engage the tubular members 13 where they pass therethrough. For this reason, it is desirable to crimp each slat, as shown at 42 in Figure 3, where it passes through the slit in the tubular member 13. The crimped portion 42 engages the edges of the slit 41 and prevents in and out motion of the slat relative to the tubular member.

As already described in connection with Figure 1 a seat 12 may be secured to a chair frame of the type described by resting it on the straight top rungs 4 and 10. An alternative method of supporting a seat, in this case a deeply upholstered one, is shown in Figures 7 and 8. The seat is supported by front and rear rungs as previously described, but in this instance, the rungs 43 and 44 are bowed inwardly to extend a considerable distance within a line connecting the legs. In the particular embodiment disclosed in Figure 7, the seat cushion is retained against lateral displacement by legs 1a and 2a, and is retained in position against displacement fore and aft by curved rungs 45 and 46.

Referring now to Figures 11 and 12, I have shown an adaptation of my tubular construction to the legs of a card table on which small trays 55 are mounted to serve as supports for smoking accessories or similar purposes. As shown in

Figure 12, the table top comprises a flat member 56 of appreciable thickness which may be constructed of wood and which may be covered with a thin surface material 57 of linoleum or any desired covering. Each leg of the table is constructed, as previously described in connection with the chairs, of tubular members 13b joined together by washers 14b and 15b and a central clamping rod 22b. The legs may be secured to the table top by passing the rod 22b through the table and screwing a nut 58 thereon, this nut being countersunk into the top of member 56 so as not to protrude above the surface thereof. A washer 59 having a downwardly extending flange may be used between the member 56 and the uppermost tubular section 13b to prevent the edges of the tubing from cutting into the material 56. It will be apparent that with the construction disclosed, the tubular section 13b will be clamped firmly together between the washers 14b and 15b when the rod 22b is tensioned. This tensioning may be accomplished by screwing a nut on the lower end of rod 22b and bearing against the lower end of the lower section 13b, as was described in connection with Figure 2.

To support the trays 55, each washer 14b is provided with a central shoulder 60 extending downwardly therefrom and contacting with the cooperating washer 15b. By this construction the peripheral portions of washers 14b and 15b are separated to form a peripheral groove. Each tray 55 is provided with a drilled hole at its inner end, of substantially the same diameter as the circular shoulders 60 on washers 14b, and at the time the table leg is assembled the tray 55 is

positioned between the washers 14b and 15b, the shoulder 60 on washer 14b fitting into the drilled hole in the tray 55.

Where the tray 55 is very small the construction described forms sufficient support for it. The tray being supported between the washers 14b and 15b against vertical motion, although it is free to rotate about the legs. However, unless the tray 55 is very small in size, it is desirable to brace it, and this may be done by the use of a brace 61 rotatably secured between a second set of washers 14b and 15b positioned below the washers engaging the tray directly as shown in Figure 12. The upper part of the brace 15 61 is secured to the tray 55 by being riveted or welded thereto. Since both the tray 55 and the brace 61 are free to rotate about the leg of the table, the entire assembly may be rotated under the table top out of the way or outwardly, all as 20 shown in Figure 11.

I claim:

1. In furniture construction a pair of spaced apart frame members each comprising a tubular element, a pair of washers mounted at one end 25 of each of said tubular elements, said washers forming therebetween a laterally extending aperture, a rod extending throughout the length of each of said tubular elements and passing through said washers, a third frame member 30 joining said first frame members and comprising a pair of terminal connecting elements each having an extension positioned in the aperture between said washers, and each extension having a laterally extending hole through which the rod 35 associated with said washers passes, the faces of said connecting elements which are toward each other each having a seat thereon, a tubular member comprising at least one section extending between said terminal connecting elements and having 40 its ends positioned in said seats, and a rod concentrically positioned within said last-named tubular member and threaded at its opposite ends into said respective connecting elements, whereby said last-named tubular member is compressed 45 between said connecting elements.

2. An element of furniture construction comprising a pair of spaced apart tubular leg elements having central retaining rods, a rung element joining said leg elements comprising a 50 plurality of tubular members positioned end to end, washers between said members having seats for receiving and centering juxtaposed ends of said members with respect to each other, a central rod having threaded ends positioned within said 55 plurality of tubular members, a plug in each outer end of the terminal tubular members, said plugs having shoulders resting against the ends of said terminal tubular members and having longitudinal threaded apertures for screwing onto the 60 threaded ends of said central rod, and the plugs in said ends having registered holes therethrough to be engaged by the central retaining rods in said spaced apart tubular leg elements whereby said plugs are permanently locked with respect 65 to said rungs.

3. In furniture construction a pair of spaced apart frame members each comprising a pair of hollow elements positioned end to end, the juxtaposed ends of said hollow elements forming there- 70 between a laterally extending opening, a rod ex- tending throughout the length of each of said

frame members and passing through said hollow elements, a third frame member joining said first frame members and comprising a pair of terminal connecting elements each having a portion thereof positioned in the respective aperture between said hollow elements and each of said portions having a laterally extending aperture through which the rod associated with said hollow elements passes, a tubular member comprising at least one section extending between said terminal connecting elements and abutting against said connecting elements, and a rod concentrically positioned within said last-named tubular member and threaded at its opposite ends into said respective connecting elements whereby said last-named tubular member is compressed between said connecting elements.

4. An article of manufacture comprising a hollow frame member formed by a plurality of tubular elements arranged in end to end relationship, an inner rod extending longitudinally through said elements, contiguous element engaging washers slidably mounted on said rod between said elements and provided with means for holding said elements in alignment, a hollow cross member having an end located between and supported by said washers and pierced by said inner rod, and means on the opposite ends of said first named inner rod and cooperating with the associated ends of the tubular elements for clamping all of said parts together and positioning them on said rod.

5. An article of manufacture comprising a hollow frame member formed by a plurality of tubular elements arranged in end to end relationship, an inner rod extending longitudinally through said elements, element engaging washers slidably mounted on said rod between said elements and provided with means for engaging the ends of said elements and holding said elements in alignment, a hollow cross member having an end located in and supported by said washers, an inner rod extending longitudinally through said cross member, a connector secured to the end of the inner rod of said cross member and slidably mounted on the inner rod of said frame member, and means on the opposite ends of the inner rod of said frame member and engaging the ends of the associated elements for clamping all of said parts together and positioning them on said rod.

6. A joint construction for furniture comprising a pair of tubular members positioned in alignment, a pair of washer elements inserted between adjacent ends of said tubular elements and having circular flanges thereon for receiving and fitting the ends of said tubular members, said washers together forming a laterally opening aperture therebetween, a lateral tubular member having an end fitting into said aperture, the portion of said end lying between said washers having a laterally extending aperture therethrough, and means comprising a rod extending through said first named tubular members, said washers and said aperture in the end of said lateral tubular member, together with tensioning means on the ends of said rod bearing against the outer ends of said tubular members for clamping said washers together about said laterally extending tubular member.

WARREN MCARTEUR, JR.
